UNITED STATES PATENT OFFICE.

RALPH K. FOX, OF NORTHWOOD, IOWA.

EXTENSIBLE SUSPENDING-FRAME.

1,232,911.

Specification of Letters Patent. Patented July 10, 1917.

Application filed August 9, 1915. Serial No. 44,578.

To all whom it may concern:

Be it known that I, RALPH K. FOX, a citizen of the United States, residing at Northwood, in the county of Worth and State of Iowa, have invented certain new and useful Improvements in Extensible Suspending-Frames, of which the following is a specification.

This invention relates to a combination suspending frame which is capable of a variety of particular uses and especially as a portable clothes line rack, a quilting frame and a curtain stretcher.

As a principal object, it is contemplated by this invention to provide a number of longitudinally extensible frame bars adapted to be connected by end bars upon which a clothes line may be strung or curtains and quilts supported, the latter during the making of the quilt.

More specifically, it is an object to provide connecting means between the end bars and respective supporting bars and to hingedly connect the first named bars at each end of the frame in order to permit of their being readily folded to occupy the minimum amount of space when not in use.

Still more specifically, it is an object of this invention to provide the hinged end bars of the frame with inclined grooves or a series of spaced apertures to accommodate respectively the hooks adapted to support the clothes line, curtains or the like in various embodiments of the frame.

The above and additional objects which will become apparent as this explanatory description proceeds, are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention as it is reduced to practice, and throughout the several views of which like characters of reference designate similar parts:

Figure 1 is an elevational view of the frame of this invention as arranged for the suspension of a clothes line;

Fig. 2 is a transverse sectional view of the same subject-matter taken on the line 2—2 of Fig. 1;

Fig. 3 is a perspective detail of an exten-

sible brace, the employment of which is desirable to prevent sagging of the frame;

Fig. 4 is a sectional detail of the adjusting means for the extensible bars, taken on the line 4—4 of Fig. 1;

Fig. 5 is a view showing the device arranged for use as a quilting frame;

Fig. 6 is a detached elevational view of a pair of the hinged end bars;

Fig. 7 is a sectional view taken on the line 7—7 of Fig. 6;

Fig. 8 is a perspective view of one of the removable quilting frame bars;

Fig. 9 is a fragmentary perspective of a portion of one of the end bars showing the manner of mounting the curtain stretcher hooks, and

Fig. 10 is a sectional view of the same matter showing the manner of mounting the clothes line hooks.

In the embodiment of the suspending frame illustrated, there are employed a pair of extensible base members 15 and a substantially similar upper member 16. Each of these members includes a pair of bars 17 and 18 which are slidably connected with each other through the medium of strap brackets or stirrups 19, one stirrup being carried by each bar to slidably embrace the coacting bar of the extensible members. Adjustment of the sliding bars 17 and 18 is made as shown particularly in Fig. 4, through the use of a set screw 20 which extends through the bar 17 for frictional engagement with the coacting bar 18, in order to maintain the bars in any extended position.

The outer extremities of each of the bars forming the upper member 16 are reduced and have removably connected thereto through the medium of suitable bolts 21, connecting straps 22 which accordingly depend from each extremity of the composite member 16 for the support of the end members illustrated as a whole in Fig. 6 and designated 23, the somewhat shorter base members 15 having similarly secured thereto laterally projecting straps 24. The connections between the straps 24 and the end members 23 are made in each case by removable bolts provided with the wing nuts 25 to facilitate the operation of assembling or unjoining the frame.

The end member shown in Fig. 6 includes a pair of bars or legs 26 and 27, suitable hinge connections being formed at their

adjacent upper extremities by the employment of a piece of strap metal 28 bent as indicated in this figure. The bar or leg 26 is provided at each extremity with an aperture 29 which is adapted to be secured by the mentioned removable fasteners when positioned between the various connecting straps of the members 15 and 16. The pivoted bars 27 are adapted to be extended backward as 10 supporting legs for the remainder of the structure after the manner of an easel, as shown in Fig. 2. Braces securing the easel legs to their respective bars 26, when extended, include a strap 30 pivoted to each 15 easel leg and formed at the opposite extremity with a key-hole slot 31 for removable engagement with a pin 32 adapted to project from each corresponding bar 26. Since this pin would otherwise interfere 20 with the complete folding of the legs 26 and 27, both the brace 30 and the adjacent portion of the leg 27 are recessed as denoted by the numeral 33 for the reception of this pin 32 as may be readily grasped from Figs. 6 25 and 7. Braces 30^a are pivoted to each member 26 in order to engage the upper horizontal member of the frame in rigidly maintaining the alinement thereof. As thus set 30 up, it will be apparent that the end members may be readily separated by an extension of the base members 15 and of the upper member 16. A central brace illustrated in detail in Fig. 3 and denoted by the numeral 34 includes a pair of sliding bars 35, the outer extremities of which are each 35 rectangularly notched as denoted at 36 in order to contact with the opposed edges of the main frame, considering the latter to include the upper member 16 and the forward base member 15, such main frame being supported by the bars or legs 27 and the rearward base member 15. Stirrup 40 brackets 37 are employed to slidably connect the bars 35 of this intermediate brace and an adjusting screw 38 is furnished with 45 the wing nut to control the extension of these members.

Having thus set forth the main characteristics of the portable and adjustably extensible frame of this invention there now remains to describe the manner of fitting the same for a number of particular uses, including embodiments as a clothes line support, a curtain stretcher and a quilting frame.

Both bars or legs of each of the end members 23 are provided with a longitudinal inclined groove 39 near one edge and with a series of small recesses 40 adjacent the opposite edge for the purpose of accommodating therein the respective hooks 41 and 42, as is illustrated to advantage in Figs. 9 and 10. The hooks 41 are adapted to be used for the purpose of stretching a curtain or similar article between the end members

and are adjustable in the groove 39 in order that they may be moved to engage the curtain edges at the proper points demanded by the pattern thereof. The hooks 42 are smaller and are seatable within the spaced 70 apertures 40 for the purpose of stretching clothes lines from one end member to the other. Similar hooks 42^a are also provided on each of the bars 35 comprising the central brace 34, as is shown in Fig. 3.

As is shown in Fig. 1 each pair of horizontally alined hooks upon opposite end members are adapted to be connected with a separate rope or clothes line porton 43. Each of these ropes has a loop or eyelet 44 formed in one extremity for engagement with one of the hooks 42 of each stated horizontal pair while the opposite extremity 45 is secured in a plate 46 which is otherwise slideable upon the intermediate portion of the rope. As shown in Fig. 1, a bight portion 47 between the extremities 44 and 45 may be formed upon each rope for engagement with the remaining hook 42 of the bar to be connected, by sliding an eyelet 48 toward 90 the hook member to be engaged in the manner which should be obvious. Each clothes-line thus supported by a hook on each of the end members is individually extensible so that the portable frame may be set up in 95 various rooms of a house to dry clothes hung therefrom when weather conditions are externally unfavorable. The frame may be expanded or contracted in the usual manner to suit the size of the room into 100 which it is placed and the clothes-lines being each idividually adjustable may be quickly and easily tensioned to the adjustment of the frame with much greater ease and less time and trouble than would be the case if 105 a continuous rope were used and supported on hooks of the two end bars.

When adapting the supporting frame of this invention for quilting purposes the end members 23 should be removed and replaced by the shorter bars 49 illustrated in Fig. 8 and adapted to be connected in the obvious manner with the straps 22 and 24 of the upper member and one of the base members 15, respectively. A series of apertures 115 50 are formed in each of the members 15 and 16 to permit change of position of bolts 20 and 21 so that the extensible frame may be suitably adjusted for quilting purposes.

From the foregoing, it should be apparent 120 that the frame of this invention is readily portable, may be readily taken apart, and as readily folded, as circumstances may dictate. Each of the end members being secured to a separate member of the upper 125 bar, it will be seen that when the legs or bars of said end members are folded upon themselves in the manner of Fig. 6 they can readily be folded upon the parts of the upper member to which they are secured 130

through the medium of the straps 22. In all cases a portable suspending frame is provided, which is also extensibly adjustable in order to fulfil all the requirements of a clothes line support, a curtain stretcher, and a quilting frame in the manner set forth.

While in the foregoing, however, there has thus been illustrated in the drawings and described in the specification such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

What is claimed is:—

1. A suspending frame comprising an upper extensible member and two extensible base members, end members formed of two bars or legs pivotally connected together at their upper ends, separable and pivotal connections between one of the bars of each end member and the end of the upper member, separable connections between the lower ends of the same end bars and one of the base members, similar connections between the other base member and the remaining bars of the end members, a longitudinal slot in each of the first-named bars of said end members, a row of perforations in the same bars parallel to said slots and similar rows in the other bars of the end members, hooks slideable in said slots for the attachment of fabrics to be stretched, other hooks fitting in said perforations, and ropes adjustable longitudinally and adapted to be connected onto a hook in an opening in the opposite side members.

In testimony whereof I affix my signature in presence of two witnesses.

RALPH K. FOX.
